ADJUSTABLE PROPELLER

William Louis Effinger, Jr., West Hempstead, N. Y.

Application May 11, 1943, Serial No. 486,493

5 Claims. (Cl. 170—160)

My invention is an improvement in propellers which are particularly adapted for use in model airplanes, although the constructions involved render it adaptable for use in connection with boats, fans and other devices. In the accompanying drawing, I have illustrated the best form in which I have contemplated embodying the invention, together with a slight modification thereof, and the said invention is fully disclosed in the following description and claims. The structures illustrated in the accompanying drawing are particularly adapted for use in connection with model airplanes and for convenience will be described with reference thereto.

In the accompanying drawing,

Fig. 1 is a view illustrating the parts of my improved propeller separated from each other for convenience of description.

Fig. 2 is a sectional view of one of the blades on the line 2—2 of Fig. 1.

Fig. 3 is a view partly in section showing the complete propeller assembled.

Fig. 4 is a sectional view taken on the line 4—4 of Fig. 3 through one end of the hub.

Fig. 5 is a sectional view of one of the blades taken on the line 5—5 of Fig. 3.

Fig. 6 is a similar section of the blade on the line 6—6 of Fig. 3.

Fig. 7 is a similar sectional view of the blade on the line 7—7 of Fig. 3 adjacent to its outer end.

Fig. 8 is a partial view of a modification in which a different form of hub is employed in connection with three blades similar to those shown in Fig. 3.

Fig. 9 is a detailed view of the hub of the propeller shown in Fig. 8.

Figs. 10, 11 and 12 are detailed views showing a section of one of the propeller blades in adjusted positions for varying the pitch thereof.

Referring now to the construction of the propeller, 1 represents the propeller hub which is preferably of general cylindrical form and is provided at its opposite ends with inwardly tapered recesses 2—2. The hub 1 is also provided with a central passage 3 to receive the driving shaft of the propeller. The propeller blades are indicated at 4—4, and each is provided with a hub engaging portion 4a, having tapered sides, as indicated at 4b, the said hub engaging portion being of slightly greater width than the portion of the blade immediately extending outwardly therefrom, it being understood that the hub engaging portion will be flexed into curved form so as to fit within one of the tapered recesses

2 in which it may be secured by means of a plug 5, as clearly shown in Fig. 3. The main body of each blade 4 is of the usual propeller blade form, and the portion indicated at 4c adjacent to the leading edge 4d is slightly narrower than the portion 4e on the opposite side of the longitudinal axis of the blade, as clearly shown in Fig. 1. When the hub engaging portions of the blade are inserted in the tapering recess 2 of the hub, the blades will be transversely curved throughout the main portions of the length of the blade to different extents as indicated in Figs. 5, 6 and 7, the transverse curvature of the blade being greatest adjacent to the hub portion and gradually flattened toward the outer end of the blade to accommodate the different peripheral speeds of the blades from the hub engaging portion to the outer end of blades where obviously the peripheral speed will be greatest. It will be readily understood that the pitch of each blade can be altered by partially rotating the hub engaging portion 4a in the recess 2 which it engages, so as to vary the pitch as desired, and this can be done by loosening plug 5 or removing it, after which the plug is reinserted firmly so as to lock each blade in its adjusted position. Figs. 10, 11 and 12 illustrate the variations in the position of the blade under various adjustments of the pitch thereof.

30 The pitch may be canged in order to obtain the desired or maximum performance. Obviously,

low pitch gives fast climb. High pitch gives long,

fast flight and medium pitch gives best all around

performance of the propeller. In adjusting the

35 propeller blades in the respective recesses 2, the eccentricity of the said recesses will assist in securing the desired adjustment of the blades.

A particular advantage of this construction is that especially in the application of it to

40 model airplanes the adjustment of the propeller blades obtains the best results desired and can be readily accomplished in the manner previously described, after which the relation of the blades to the hub may be made permanent by securing

45 the plugs 5 within the recesses 2 by gluing them or by the use of any other desired fastening means.

In some instances it is found convenient to insert the hub engaging portions of the blades in the hub recesses 2 in which they will be frictionally held by reason of the tapered walls of

50 said recesses so that the desired adjustment of the blades may be obtained before the plugs 5 are inserted, after which the plugs may be inserted and permanently secured in the hub if

55 desired.

In Figs. 8 and 9 I have illustrated a modification of the invention in which the hub indicated at 101 is provided with three or more tapering recesses 102 to receive an equal number of propeller blades constructed in the manner shown in Figs. 1 to 7 and previously described, the blades being indicated in Fig. 8 at 104. The hub 101 is provided with an axial passage therethrough indicated at 103 for the passage of the propeller shaft and the blade receiving recesses 102 will be equally distributed around the axis of the aperture. The method of adjusting the individual blades of the propeller will be the same as hereinbefore described.

In carrying out my invention the propeller blades may be formed of any suitable sheet material, but I have found in practice that for use in model airplanes it is desirable to form the blades of tough, resilient, stiff paper, such as fibreboard or bristol board. This material is inexpensive and light in weight, and has sufficient flexibility that the flat blank (Fig. 1) can readily be bent into the curved form of the propeller blade (Figs. 3 to 7), while having sufficient body, stiffness and rigidity to maintain this form during use. A further advantage is that the edge of the material is not sharp and there is hence no danger of fingers being cut by a rapidly rotating propeller. The hub is preferably formed of wood, but may if desired be made of metal, plastic or other suitable material.

What I claim and desire to secure by Letters Patent is:

1. The herein described model propeller comprising a streamlined hub having inwardly tapered blade receiving recesses, propeller blades formed from flat sheet material and each having a curved hub engaging portion for engaging one of said recesses in the hub and frictionally held therein to permit the blades to be rotated in said recesses to vary the pitch of said blades, and inwardly tapering plugs coaxial with said recesses for engaging the curved hub engaging portion of each blade and releasably locking it with respect to the hub.

2. In a propeller for a model airplane, the combination of a hub having an inwardly tapered

blade receiving recess, an inwardly tapered plug fitting into said recess, and a blade formed from flat, resilient sheet material and having a hub engaging portion, said hub engaging portion being held between said plug and the wall of said recess to secure said blade to the hub and to hold said blade in curved position, the taper of said recess and plug and the resilience of said blade material cooperating to cause the transverse curvature of the blade to decrease progressively toward the tip of the blade.

3. The herein described model propeller comprising a hub provided with inwardly tapered blade receiving recesses and a plurality of blades formed from inherently flat, flexible sheet material having hub engaging portions flexed into position to fit within one of said tapered recesses and to be frictionally held in position therein to permit each blade to be adjusted rotarily within its tapered recesses in the hub to vary the pitch of the blade, and a tapered plug removably fitting within the hub engaging portions of each blade for releasably locking the blade in adjusted position with respect to the hub.

4. In a model propeller, the combination of a hub, provided with an inwardly tapered blade receiving recess of circular cross section, an inwardly tapered circular plug fitting into said recess, and a blade formed of inherently flat, resilient sheet material and having a hub portion adapted to be held between said plug and the wall of said recess, said blade being flexed and held in curved position against the resiliency of the material by engagement of said plug and recess wall with said hub portion, said resiliency causing the transverse curvature of the blade to vary inversely to the distance from the hub.

5. In a propeller for a model airplane, the combination of a hub having an inwardly tapered radial blade receiving recess, an inwardly tapered plug fitting into said recess, and a blade formed of inherently flat, resilient fibrous sheet material, said blade being held resiliently flexed in curved position by engagement of a hub portion of the blade between said plug and the wall of said recess.

WILLIAM LOUIS EFFINGER, JR.
